HIS ATTORNEYS

UNITED STATES PATENT OFFICE.

WILLIAM C. FISCHER, OF CLEVELAND, OHIO, ASSIGNOR TO THE BAKER-RAULANG COMPANY, OF CLEVELAND, OHIO, A CORPORATION OF OHIO.

WINDOW MOUNTING.

Application filed April 30, 1923. Serial No. 635,439.

To all whom it may concern:

Be it known that I, WILLIAM C. FISCHER, a citizen of the United States, residing at Cleveland, in the county of Cuyahoga and 5 State of Ohio, have invented certain new and useful Improvements in Window Mountings, of which the following is a specification, reference being had therein to the accompanying drawings.

10 This invention relates to window mountings and is especially concerned with a guide channel member for sliding windows of various thicknesses.

One object of the invention is to construct 15 a resilient mounting and retaining member or channel for windows which is capable of deformation to receive windows of different thicknesses.

Another object is to construct a resilient 20 window mounting or retaining member of a substantially uniform size which can be fitted to bear against windows of different thicknesses with predetermined pressure.

A further object is to construct a substantially U-shaped resilient guide channel and 25 retaining member for sliding glass windows adapted to guide and retain sliding windows of various thicknesses.

Other objects and advantages will be 30 pointed out hereinafter and structure embodying the same described by what is claimed.

For purposes of disclosing my invention to those skilled in the art, I have chosen for 35 a detailed description a device embodying my invention and for use with a sliding window of an automobile, in which:

Fig. 1 is a side elevation of an automobile door having a sliding window and provided 40 with my improved channel member.

Fig. 2 is a sectional view taken on line 2-2 of Fig. 1.

Fig. 3 is a side view partly broken away 45 of the channel member shown in Figs. 1 and 2.

Figs. 4 and 5 are fragmentary sectional views similar to Fig. 2 showing the channel member adapted to windows of different thicknesses.

50 Fig. 6 is a fragmentary sectional view similar to Figs. 2, 3 and 4 but showing my improved channel member assembled in a groove in a window frame.

Fig. 7 is a fragmentary view of a modified

form of channel securing and adjusting means.

Referring to the drawing, 1 designates an automobile door having frame 2 and a window 3 adapted to slide up and down in the frame. The frame 2 is provided with a recess 4 along each of its opposite sides, in each of which a window mounting retaining or channel member 5 is mounted to receive window 3. Securing means, such as tacks 6, may be driven through channel member 5 and into frame 2 to retain the members in the desired position in the recesses. An adjustable frame member, or strip of molding 7 engaging or bearing against the side of each channel member 5, furnishes one wall 70 of recess 4 and also serves other purposes later to be described.

Channel member 5 comprises an elongated strip of resilient material, preferably molded rubber, having a distortable bottom portion 8 and upstanding self supporting side portions 9 substantially parallel to each other. Adjacent the point of junction of each side portion with the bottom portion a small lengthwise extending recess 10 is formed in the inner surface of the bottom portion. The inner surfaces of member 5 are preferably covered or lined with a material substantially antifriction to glass, for example, fabric which preferably is imbedded in the 85 rubber.

In applying this channel member to a frame 2 a strip of the requisite length, preferably as long as the window and, if desired, long enough to accommodate the window in 90 either fully opened or fully closed position is secured in recess 4, and the window is assembled in the frame with its side edges between side portions 9 of channel member 5. Then frame member 7, which may be a 95 piece of molding as long as the channel member, is brought into engagement with one side portion 9 and pressed thereagainst sufficiently to bring the side portions 9 into the desired proximity to window 3, or in 100 other words, to cause these portions to exert a predetermined pressure on the window. When the window is relatively thick only slight pressure may be required from the member 7 against member 5, the relative location and shape of parts of such condition being shown in Fig. 2. When the window is thinner, however, the pressure of member 105

7 against side portion 9 causes a distortion of bottom portion 8 which results in substantially parallel movement of the side portions toward each other and outwardly with respect to the bottom portion. Positions assumed by sides 9 under different degrees of compression or with windows of different thicknesses are indicated in Figs. 4 and 5, where the side portions are still substantially parallel but extended somewhat farther beyond the frame than in Fig. 1 and the bottom portion is distorted.

By varying the pressure applied by member 7 and consequently the amount of distortion of the bottom portion 8 and movement of side portions 9 toward each other, windows of various thicknesses can be accommodated with the same closeness of fit, or the closeness of fit of a given window may be varied.

The lining 11 forms a surface for a window substantially without friction to glass and hence is preferable for sliding windows where contact of the rubber member 5 with the window would prevent easy smooth movement of the latter. However, it may be advantageously employed where the window is stationarily mounted because of its adjustability, resiliency, and non water conducting properties.

In Fig. 6 I have illustrated a window frame 12 having a groove 14 formed therein in which my improved channel member 5 is mounted and assembled with a window 3. In a groove of fixed dimensions, as here, the closeness of fit between member 5 and window 3 will be more or less determined by the sizes of groove and window and is not adjustable as in the preceding modification of frame.

Although I have described my invention as embodied in a channel member for sliding windows, I do not intend to restrict it to such use only, since, due to its adjustability to windows of various thicknesses, it may be utilized wherever a resilient window mounting is desired.

My improved channel member is of a form and shape which is suited to commercial machine production and when the sides are resilient and flexible, can be rolled or wrapped conveniently and compactly for shipment. The channel member may be manufactured in a single standard size and yet be suitable for use with windows of various thicknesses because of its adjustability.

Although I have shown and described the side portions 9 of channel member 5 as being composed of resilient material, I contemplate also the use of relatively stiff or rigid side portions, as hard rubber, with a resilient, distortable bottom portion as described.

In Fig. 7 I have illustrated modified means for securing my improved channel

member in a window frame where no channel recess is provided in the frame. 15 designates members, preferably metal, which may be secured adjustably to the window frame 16 as by screws 17 and between which members guide channel 5 is fixed. By adjusting the position of members 15 toward or away from each other the side portions 9 of member 5 may be adapted to windows of various thicknesses as previously described.

In the foregoing specification I have disclosed my invention in connection with a window for an automobile but by so doing I do not wish to be understood as limiting my invention to windows only. It will be obvious to those skilled in the art that my invention is applicable wherever any one or more of the properties of my improved channel are useful, for example, in mounting steel plates, sliding window screens or shutters, non-transparent glass, celluloid and various other materials and objects.

Having thus described my invention what I desire to secure by Letters Patent is set forth in what is claimed.

What is claimed is:

1. As a new article of manufacture, a resilient, molded rubber, channel shaped guide member for sliding windows, comprising a distortable bottom portion and substantially parallel side portions movable parallelly toward and away from each other, the said member having normally open depressions molded therein between the said bottom and side portions and at the side edges of the said bottom portion, the depressions being adapted to be closed as the side portions are moved parallelly toward each other, and anti-friction material lining the inner surfaces of the said bottom and side portions.

2. As a new article of manufacture, a resilient rubber channel member for sliding windows comprising a bottom portion and substantially parallel side portions integral therewith, the said member having normally open, longitudinally extending depressions located at the side edges of the bottom portion, the said depressions constituting grooves which are adapted to be closed as the sides are moved parallelly toward each other, and a liner substantially antifriction to glass integrally connected to the inner surface of the said side portions.

3. In combination with a window frame, a window retaining member formed of resilient material and comprising a distortable bottom portion and upstanding side portions integral with opposite side edges of the said bottom portion, the member having longitudinally extending grooves formed on its inner side along the side edges of the bottom portion, and a frame member adjustably fixed to said window frame and cooperating therewith and with the said member to distort the bottom portion of the said member

and close up the said grooves while moving the said sides parallelly towards each other.

4. As a new article of manufacture, a molded rubber window mounting and retaining member comprising a resilient distortable bottom portion, upstanding self supporting, side portions formed integrally with the side edges of the said bottom portion and partially separated therefrom on their inner sides by grooves extending along the side edges of the bottom portion, and a liner substantially antifriction to glass integrally connected to and embedded in the inner surface of the said member to prevent substantial engagement of a glass window with the rubber of the member.

5. In combination with a window frame, a window retaining member formed of resilient material and comprising a distortable bottom portion, upstanding side portions formed integrally with the bottom portion and partially separated therefrom by grooves formed on the inside of the member between the side edges of the bottom and side portions, and a frame member cooperating with the said window frame and the said retaining member to move the said side portions parallelly toward each other, the bottom portion being distorted and the said grooves being closed as the sides move toward each other.

6. A guide member for a sliding glass window, consisting of a resilient member formed

with a body portion and upstanding, self-supporting, longitudinal side portions to 35 provide a channel to receive the edge of a sliding window glass, the sides being automatically self-adjustable in parallelism within the range of thicknesses of commercial automobile window glass to maintain 40 a firm but yielding grip upon any glass within such range, and a flexible material, relatively thin, as compared with the thickness of the said side portions and substantially anti-friction to glass, permanently and securely bound to the inner surfaces of the bottom and side portions of the channel member to form an integral unitary structure with said channel member, adapted to endure for the normal life of an automobile. 50

7. As a new article of manufacture, a resilient rubber channel member for a sliding window pane comprising a bottom portion and substantially parallel side portions automatically self-adjustable bodily in parallelism to yieldingly engage window glasses of thicknesses within a considerable range, and a thin foraminous liner anti-friction to glass, bound to the inner surface of the same by parts thereof penetrating into the formations of the said liner and interlocking therewith. 55

In witness whereof I hereunto affix my signature this 27 day of April, 1923.

WILLIAM C. FISCHER.
